UNITED STATES PATENT OFFICE.

BASIL E. DRUMMOND, OF HOLDEN, WEST VIRGINIA.

RAIL BENDER.

1,413,527.

Specification of Letters Patent. Patented Apr. 18, 1922.

Application filed November 4, 1920. Serial No. 421,732.

To all whom it may concern:

Be it known that I, BASIL E. DRUMMOND, a citizen of the United States, residing at Holden, in the county of Logan and State 5 of West Virginia, have invented certain new and useful Improvements in Rail Benders; and I do hereby declare the following to be a full, clear, and exact description of the invention, such as will enable others skilled 10 in the art to which it appertains to make and use the same.

This invention relates to new and useful improvements in rail benders and has for its primary object the provision of means 15 for moving the bender along the rail when the former is in adjusted position or when placing the necessary pressure on the rail to bring about the desired bend, thereby obviating the necessity of adjusting the 20 bender each time it is moved from one point to another on the rail.

Another object of this invention is the provision of a rail bender of the above stated character which will be simple, durable and efficient, and which may be manufactured and sold at a comparatively low 25 cost.

With these and other objects in view as will become more apparent as the description 30 proceeds, the invention consists in certain novel features of construction, combination, and arrangement of parts as will be hereinafter more fully described and claimed.

35 For a complete understanding of my invention, reference is to be had to the following description and accompanying drawings, in which:—

Figure 1 is a top plan view illustrating 40 a rail bender constructed in accordance with my invention,

Figure 2 is a bottom plan view illustrating the same,

Figure 3 is a transverse sectional view 45 taken on the line 3—3 of Figure 1,

Figure 4 is a longitudinal sectional view taken on the line 4—4 of Figure 1,

Figure 5 is a detail sectional view illustrating the ratchet mechanism,

50 Figure 6 is a detail sectional view taken on the line 6—6 of Figure 1.

Figure 7 is a sectional view taken on line 7—7 of Figure 5.

55 Figure 8 is a detail view, illustrating a handle.

Referring in detail to the drawings, the numeral 1 indicates a substantially triangular shaped frame, having secured thereto spaced axles 2 which are located adjacent each end of the bight portion 3 of 60 the frame and has journaled thereon flanged wheels 4 adapted to engage one side of the ball 5 of a rail 6. The apex portion 7 and the bight portion 3 of the frame 1 are connected by spaced guide bars 8 between which 65 is slidably mounted a head 9. The sides of the head 9 are provided with grooves 10 to receive the guide bars to permit free sliding movement of the head towards and from the rail 6. The head is provided with a removable flange 10' so that said head may be removed from the guide bars 8. The outer ends of the axles 2 are supported by braces 11 which are riveted or otherwise secured to the bight portion 3 of the frame and 70 are offset as illustrated at 12 to permit free rotation of the flanged wheels 4.

A feed screw 13 has swivel connection with the head 9 and extends through an opening 14 formed in the apex portion 7 of the frame 1, which opening is provided with feed threads and the outer end of the feed screw 13 is provided with a head 15, which has openings 16 through which a handle 17 may be passed for rotating the 80 feed screw to move the head 9 towards and from the rail 6. The handle 17 has one end pointed as illustrated at 18 to facilitate the insertion of the same in any one of the openings 16 of the head 15. The handle 17 is also removable from the head 15 for the purpose of operating a ratchet mechanism 19 which will be hereinafter more fully 85 described.

An axle 20 is secured to the head 9 and has 90 journaled thereon a grooved wheel 21 adapted to engage the rail 6 upon an opposite side from the side engaged by the wheels 4 and the latter are preferably of the flanged type. The axle 20 is supported by a brace 21'. 100 The wheel 21 is provided with spaced flanges 22' to define the groove and are adapted to engage the outer and inner faces of the ball 5 of the rail 6. One face of the wheel 21 has formed thereon counter sunk gear teeth 22 adapted to mesh with a pinon 23 journaled on a stub shaft 24 carried by bearings 25. The bearings 25 are secured to the head 9 upon opposite sides of a slot 26 which permits the pinon 23 to extend through the 105 110

- head for engagement with the gear teeth 22 upon the wheel 21. A forked member 27 is journaled on the stub shaft 24 and straddles the pinion 23 and carries a spring actuated 5 double end dog 28 adapted to ratchet over the pinion 23 in one direction and adapted to bight or grip the teeth of said pinion when moved in an opposite direction so as to bring about rotation of the wheel 21 when desired.
- 10 The dog 28 is capable of operation in a reverse direction. The forked member 27 is provided with a tubular portion 29 to receive one end of the handle 17 when it is desired to operate the ratchet mechanism 19.
- 15 In operation, the frame 1 is disposed over the rail 6 with the flanged wheels 4 in engagement with one side of the rail and with the wheel 21 in engagement with the other side of said rail, and by turning the feed 20 screw 13, the desired pressure or tension may be placed on the rail to bring about the desire bend in said rail. After the rail has been bent at one point and it is desired to further bend the rail at another point, the 25 ratchet mechanism 19 is operated in the proper direction to bring about a rotation of the wheel 21 which causes the frame to move along the rail without releasing the tension on the block 9.
- 30 From the foregoing description taken in connection with the accompanying drawings, it will be noted that a rail bender has been provided which may be easily and quickly applied to a rail and the desired 35 pressure placed on the rail in a convenient manner to bring about the desired bending of the rail and also that the device may be moved along the rail from one point to another without releasing the pressure or tension of the wheel 21 on the rail.

40 While I have shown and described the preferred embodiment of my invention, it will be understood that minor changes in construction, combination, and arrangement 45 of parts may be made without departing from the spirit and scope of the invention as claimed.

Having thus described my invention what I claim is:—

1. A rail bender comprising a frame, 50 wheels journaled to said frame and engaging one side of a rail, a head slidably mounted on said frame, a rail bending wheel journaled to said head and engaging the rail upon an opposite side from that engaged by the first 55 named wheels, means for adjusting the head, gear teeth formed on the second named wheel, a pinion carried by said head and in mesh with the teeth of the second named wheel, and a ratchet mechanism for rotat- 60 ing said pinion.

2. A rail bender comprising a triangular shaped frame, flanged wheels journaled to said frame, spaced guide bars carried by said frame, a head slidably mounted on said guide 65 bars, a grooved rail bending wheel journaled to said head and engaging the rail, countersunk teeth formed on one face of said rail bending wheel, a pinion carried by said head and in mesh with the teeth, a forked mem- 70 ber pivotally mounted on the head, a spring actuated dog carried by said forked member and adapted to engage the pinion, a handle removably secured to the forked member, a feed screw carried by the frame and connected to the head, an apertured head carried by the feed screw and adapted to receive the handle for adjusting the first-named head towards and from the rail. 75

3. A rail bender comprising a frame 80 adapted to engage one side of a rail, a head mounted on the frame and adjustable towards and from the rail, a circular element carried by the head and contacting with the rail and having circularly arranged teeth, 85 and a pawl and ratchet mechanism carried by the head and engaging the teeth to rotate the circular element.

In testimony whereof I affix my signature in presence of two witnesses.

BASIL E. DRUMMOND.
